4 Claims. (Cl. 250—17)

In the present state of the art the amplification of ultra-short wave oscillations, as furnished, for instance, by a retarding field generator, can not practically be carried out in an amplifier tube because of the inertia in the movement of the electrons. For this reason, when operating with extremely short waves over a transmission line or other channel, it is necessary at the receiving end to rectify the signals before introducing amplification. Such amplification is practically limited to audio frequencies. Intermediate frequency amplification has not heretofore proven satisfactory since a beat reception can not practically be carried out by the superposition of an oscillation produced in the receiver, in view of the lack of the required constancy of the frequency. Furthermore, it is not possible to use undamped waves interrupted in the rhythm of the signals (so-called "unmodulated telegraphy", "C. W. transmission") and radiation of modulated oscillations must be relied upon. This means that the micro wave transmitter, whether in transmitting telegraphic signals or direction finding signals, etc., must be modulated with a constant frequency.

This constant audio-frequency modulation is generally carried out on the basis of the method which is also used in telephonic transmission, whereby in place of the speech currents, a constant audio-frequency, obtained for instance from a tone producer, is simply applied to the transmitter. A still simpler method resides in chopping the feed current by means of a mechanical interrupter, but the latter has the disadvantage of all mechanical, contact-establishing devices, namely that its contacts are subjected in time to considerable wear and tear. It was thought that this disadvantage was overcome by a known method, according to which the retarding field generator excites, in view of its falling current voltage characteristic, a resonance system of any frequency inserted in the retarding field circuit whereby the transmitter is likewise modulated. This method involves great difficulties, since the adjustment of the falling current voltage regions is extremely critical. Also, it does not conform to the optimum working conditions of the transmitter with regard to the carrier wave production.

All these difficulties are eliminated in a simple manner by means of the present invention, in that the retarding field generator is combined with a relaxation circuit, and that, by means of a glow tube or any other trigger relay which may also consist of electron tubes, the retarding field

generator itself produces relaxation oscillations, by which modulation is forced on the transmitter. In accordance with the invention, the charge of a condenser inserted in the circuit of the retarding field electrodes is periodically controlled by means of a trigger relay.

Figs. 1 and 2 illustrate two different embodiments of the invention.

The circuit shown in Fig. 1 serves for practically carrying out the present method of a constant auto modulation of a braking field generator. The oscillator consists of a tube R operating in a retarding field circuit, and of a resonance system L which may be placed within or outside the tube, and which will be excited in the known manner by the electron movement. In the circuit of the braking electrode B, a glow tube G1 is inserted which is bridged by a suitably variable condenser C for the purpose of determining and controlling the modulation frequency. In order to furnish the voltage required for feeding the glow tube, the tube is suitably placed at a positive bias which, for the sake of simplicity, is directly derived from the grid voltage source E_g.

The basic idea of the new method lies in the fact that the braking electrode B, which will be negatively charged when the micro waves are excited, supplies the feed voltage for the trigger relay G1. A condition is thus brought about in which the charging of the anode B and of the condenser C connected thereto can only take place up to the ignition voltage E₂ of the trigger relay G1. As soon as the glow tube is ignited, it discharges the condenser to the value of its ignition voltage E₁ whereupon a new charging takes place, and so forth. In this way the voltage at the braking electrode B fluctuates between the two voltage values E₂ and E₁, thus modulating the transmitter with the frequency of the relaxation oscillations hereby produced.

In order to more distinctly characterize the nature of the relaxation oscillations produced in this manner, the difference between the ordinary relaxation circuit will now be explained and can also be recognized in the circuit shown. The ordinary relaxation circuit operates, as is known, with a constant charging voltage E₀, charging the condenser C across a special ohmic resistance W₀ which may, in special cases, also be a vacuum tube. The relaxation period is then established by the known formula

$$T = W \times C \log \frac{E_0 - E_1}{E_0 - E_2}$$

In principle, the relaxation period in the present

case is determined by the same formula with the exception that in place of the charging resistance W there is inserted the generally non-linear inner braking resistance W_{ib} between the electrodes B and K of the generator, and in place of E_0 there must be inserted the dynamic E. M. F. in the braking circuit which depends upon the condition of oscillation of the generator. There necessarily follows therefrom, as a condition for the initiation of the relaxation oscillations, the requirement that the inner resistance of the glow tube $G!$ must be small as compared with the inner resistance W_{ib} of the generator which takes the place of the charging resistance. Only in this case is the discharge period short as compared with the charging period, otherwise a stable condition of equilibrium would be established between the charging and the discharge current.

Thus, the formula given denotes that the relaxation period of W_{ib} must be dependent upon the E. M. F. in the braking circuit. Both values, however, are a function of the condition of excitation of the retarding field transmitter, and it follows therefrom that the relaxation period must likewise change to a certain degree when the operating condition changes. Where particular stress is to be laid upon constancy of the modulation frequency, the relaxation oscillations can be stabilized by means of a resonance system S (Fig. 2) placed in series to the glow tube and tuned to the relaxation frequency.

If the transmitter is to be keyed, for instance, for purposes of telegraphy, the glow tube may be suitably switched in and shut off, as by the keying means M whereby an especially dependable initiation of the relaxation oscillations is assured. The modulation method described in the present example, for a transmitter with a single oscillator tube, can, as is obvious, be also readily applied to multi-tube transmitters, whether the individual tubes operate with regard to high frequency in parallel or in push-pull.

What is claimed is:

1. In combination, an electron discharge device comprising a cathode, anode and control electrode, means including a source of potential for supplying a high positive potential to said control electrode and a much lower potential to said

anode relative to said cathode, whereby there is pendulum motion of electrons about said control electrode, a pair of parallel wires for feeding energy from said source to said anode and to said control electrode respectively, a condenser bridged across said wires to form with said wires a resonance system, and the parallel combination of a condenser and a second electron discharge device located in circuit between said source and said wire which feeds energy to said anode, said last device being of the gas-filled type providing a discharge path for its parallelly connected condenser whenever the charge thereon exceeds the critical ignition value of said device. 5

2. In combination, an oscillation generator of 15 the retarding field type, said generator having a cathode, a grid and a plate comprised in an electron discharge tube and a source of potential so connected to said electrodes that the grid is maintained highly positive with respect to the other 20 electrodes, a resonant circuit connected between the grid and plate, a capacitor connected between the plate and a suitable point on said source of potential, and means including a gaseous discharge tube in shunt with the last said capacitor 25 for causing the oscillations of said generator to be rhythmically modulated.

3. In a system for modulating the output of a retarding field generator, an electron discharge tube having a cathode, a plate, and an intermediate electrode maintained at a high positive potential with respect to the other electrodes, a resonant network interconnecting the electrodes of said tube, means including a direct current source for maintaining said potentials on said electrodes, 30 a capacitor connected between a tap on said source and a portion of said resonant network leading to said plate, a gaseous discharge tube, and means including a key for at times causing said gaseous discharge tube to be shunted across 35 said capacitor, thereby to modulate the output energy of said generator.

4. A system in accordance with claim 3 and comprising a resonant network interposed in circuit between said key and said gaseous discharge 40 tube.

HANS ERICH HOLLMANN.
